RAZOR BLADE SHARPENER

Hyland L. Hodgson, Scarsdale, N. Y.

Application July 2, 1946, Serial No. 681,075

16 Claims. (Cl. 51—59)

1

This invention relates to a sharpener for a razor, and more particularly to a sharpener adapted to be applied to a razor of the type having a removable blade, and adapted to sharpen the blade while the said blade is assembled in the razor. Even more particularly, my invention relates to a sharpener adapted for application to a razor of the type known commercially as the Schick Injector razor for sharpening the blade of the said razor while the said blade is assembled in the razor for use.

In the Schick Injector razor a razor blade is inserted between spring surfaces that function to hold it in shaving position. The razor is so constructed that it is extremely difficult to remove a blade except through the insertion of a replacement blade, this act being carried out through the utilization of an injector magazine supplied by the manufacturer and containing a series of blades. Unlike other razors of the type having replacement blades, it is therefore impossible to remove a blade from the Schick Injector razor for sharpening except through an extremely difficult operation, unless an injector magazine is used. The injector magazines of these razors are so constructed that they cannot be refilled by the user, so that each blade replacement in the razor requires the disposal of one blade, so that considerable expense is incurred in the use of this type of razor.

I have conceived and reduced to practice a mechanism for sharpening the blade of a razor of the particular type while the blade is assembled for use in the razor. As a feature of the invention I utilize a carrier frame that may be applied and removed from the razor, the frame carrying a sharpening member that is adapted to sharpen the razor blade when the frame is assembled to the razor. As a further feature of the invention, the sharpener mechanism carried by the frame is adapted to sharpen both faces of the edge of the razor blade, with the blade held fixed in the single position it must occupy in razors of this class.

As a still further feature of the invention, I utilize a single sharpener mechanism arranged so as to sharpen both the lower and upper faces of the razor blade edge while the blade is held fixed as already emphasized. As a further feature of this part of the invention the sharpener mechanism is adapted to sharpen but one face of the fixedly held razor blade at a time, and is movable first from a position on the frame in which it sharpens one face, to a second position on the frame in which it is in contact with the other

face of the razor blade. This makes it possible to apply the frame in one position and to sharpen both faces of the fixedly held blade edge with the frame maintained in this one position.

5 As a still further feature of my invention the sharpener mechanism is mounted for transverse sliding movement on the mounting means of the frame and is preferably movable to sharpen the blade by a mere shaking of the razor when the 10 carrier frame is applied to the razor. At this point it will be well to indicate that I prefer to use a frame that is readily attached to the razor and is readily removable therefrom, but that it is within the scope of my invention to utilize a 15 frame permanently attached to the razor if desirable.

I have thus outlined rather broadly the more 20 important features of my invention in order that that the detailed description thereof that follows may be better understood, and in order that my 25 contribution to the art may be better appreciated. There are, of course, additional features of my invention that will be described hereinafter and which will form the subject of the claims 30 appended hereto. Those skilled in the art will 35 appreciate that the conception on which my disclosure is based may readily be utilized as a basis for the designing of other structures for carrying out the several purposes of my invention.

Referring now to the drawings, Fig. 1 illustrates a preferred embodiment of my invention applied to a Schick Injector razor. Fig. 2 shows my invention removed from the razor. Fig. 3 is a vertical section through the structure of Fig. 35 1 showing the relation of my sharpener to the razor and the blade assembled therein. Fig. 3a is an enlarged detail showing the relation of the sharpener to the blade per se. Fig. 4 is an end elevation of the frame mechanism of my invention. Fig. 5 is a view looking downwardly on the 40 structure of Fig. 1. Fig. 6 is a detail section taken along lines 6—6 of Fig. 3. Fig. 7 is a perspective view of a modified form of my invention while Fig. 8 is a section taken along lines 8—8 of Fig. 7.

45 Referring now more particularly to the drawings, reference numeral 10 designates a razor known in the trade as a Schick Injector razor. A removable blade 11 is applied to the razor between a spring upper plate 12 and a lower plate 13 through the utilization of an injector magazine, all as those skilled in the art will fully appreciate and understand. It is difficult to remove and replace the blade 11 except through the use of the magazine, and once a blade is removed from the magazine, and once a blade is removed from 50 a razor it is impossible for a user to put it back

into the magazine. Therefore, it is impossible to sharpen a blade 11 in the same manner as removable blades of other razors unless the user is willing to go to considerable trouble and risk serious injury through the handling of a sharp razor blade. My invention, as I have already indicated, resides in means for sharpening the blade 11 while it is assembled on the razor in the manner indicated.

My invention utilizes a carrier frame designated generally by the letter F and having a pair of side plates 14 each equipped with a guide flange 15 for guiding the frame F into assembled relation to the razor 10. Extending transversely between the forward ends of the plates 14 is a shaft 16 on which is mounted a latch member designated generally by reference numeral 17 and having a manually operated finger piece 18 and a pair of detent portions 19. It is the function of the detent portions 19 to engage the surface 20 of the razor whereby to assemble the frame F to the razor as is best illustrated in Fig. 3. For the particular purpose, the sides 14 are each formed with a struck-in lug 21 adapted to lie against the blade 11 and also against the edge of the upper spring plate 12 used to retain the razor blade 11 in position.

Each of the side plates 14 is formed with a circular bearing opening 22 in which is mounted a circular bearing member 23 having secured as an integral part thereof a pinion 24. A bearing shaft 25 is secured at 26 in eccentric relation to each of the bearing members 23, and extends transversely between the said bearing members and the two side plates 14. Mounted on this eccentric bearing shaft 25 is a sharpener carrier 27 to which a sharpener plate is secured by a screw 28. As is well illustrated in Fig. 3, the sharpener carrier 27 is adapted to be moved from an upper position illustrated in full lines in Fig. 3, to a lower position illustrated in dot and dash lines in Fig. 3. This movement is imparted to the sharpener carrier 27 by the eccentric shaft 25, and is such that the sharpener plate 29 will move from its full line position under the blade 11 outwardly into a position free of the blade, and then will move inwardly toward the blade and into contact with the upper surface thereof, all as is fully illustrated in Fig. 3. I shall now describe the means whereby the eccentric bearing shaft 25 is actuated to move the sharpener carrier as described.

Each of the plates 14 is formed with a circular opening 30 in which is mounted the circular drawn bearing portion 31 of a sector 32. Each sector 32 has formed on its periphery a series of teeth 33 adapted to mesh with the teeth of the pinion 24. In addition, the opposed ends 34 of the sector juxtaposed to the end teeth 33 thereof are so formed as to coact with surfaces 35 of the pinion 24 whereby to limit the rotation of the sector 32. This rotation of pinions 24 and bearing members 23 is limited to correspond to a full throw of the eccentric shaft 25 between its full line and dotted and dash line positions of Fig. 3. A small detent lug 36 is formed on each sector 32 and coacts with three holes 37 in each plate 14 to hold the sectors yielding in what I term an upper side position, a neutral position and an under side position. Preferably, the outer face of each plate 14 will be marked as illustrated in Figs. 1 and 2 for the purpose of designating the three positions in which the sectors may be placed. To facilitate the manipulation of the sectors, they are each formed with a finger piece having a

serrated edge 38, all as will be quite apparent to those skilled in the art.

The carrier 27 has a rearwardly extending portion 39 equipped with a relatively heavy knob 40, the utility of which will be explained presently. The portion 39 is formed also with a slot 41 having an enlarged end 42, and in this slot is positioned a shaft 43 extending between the two sectors 32. It is of course obvious that the shaft 43 serves to pivot the sharpener carrier 27 on shaft 25 as the sectors 32 are rotated by the serrated finger pieces of the said sectors, and therefore maintains the carrier in its two extreme positions of Fig. 3, and guides it while it is moving with shaft 25 between the said two extreme positions.

It will be interesting to note that the detent portion 36 of each sector 32 serves not only to maintain the sectors 32 in the three positions indicated, but also to maintain the sharpener carrier 27 in its three positions. This is accomplished through its geared relation with the bearings of eccentric shaft 25, and through the shaft 43 operating in slot 41 of the sharpener carrier. In two of these positions the carrier will be adapted to maintain the sharpener plate 29 in coaction with the upper and lower faces of the blade 11 as illustrated in Figs. 3 and 3a. In the central or neutral position of sectors 32 the sharpener plate 29 will be withdrawn entirely from the blade 11 to allow easy removal and application of the frame F to the razor 10. The sharpener carrier 27, being freely mounted for sliding movement on the eccentric shaft 25, may be reciprocated relatively thereto for the purpose of sharpening the blade 11. The function of the heavy knob 40 is to give weight to the carrier so that by a manual reciprocation or shaking of the razor 10 the carrier 27 will reciprocate relatively to the blade 11 for the purpose of sharpening the said blade. The value and utility of this action will of course be readily and clearly understood by those skilled in the art.

Referring now to Fig. 7, I illustrate a modified form of my invention. In this form of my invention I utilize a frame designated by reference numeral 50 and formed with spring clips 51 adapted to fit under the surface 20 of the razor in the same manner as the detent portions 19 of my first modification. The frame 50 is formed with a pair of side plates 52, each of which has an inward lug 53 functioning as do the lugs 21 of my first modification. Mounted on the side plates 52 are a pair of bearing members 54, one of which has secured thereto a finger piece 55. Extending between the bearing members 54 is an eccentric shaft 56, the rotation of the bearing members 54 being adapted to rotate the eccentric shaft 56 for the purpose to appear presently. It is now obvious that rotation of the shaft 56 and the two bearing members 54 may be contributed by the finger piece 55.

Rotatably and slidably mounted on the eccentric shaft 56 is a sharpener carrier 57 to which is secured by a screw 58 a sharpener plate 59.

A heavy finger piece 60 is formed as an integral part of the carrier 57, and it is the function of this finger piece 60 to induce reciprocation of the carrier 57 and the sharpener on the eccentric shaft 56, whereby to sharpen the blade. As in the first modification, the weight of the finger piece 60 is such that the shaking of the razor 10 will effect a reciprocating sharpening movement of the carrier 57 on the shaft 56. It is of course obvious that the carrier 57 is also adapted for the same type of movement bodily with the eccentric

shaft 56 as is the carrier 27 of the first modification with its eccentric shaft 25, but its rotation on the shaft is manually contributed directly through its finger piece 60 rather than automatically as in the first modification. This movement will carry the sharpener plate 59 into sharpening relation with the upper and lower surfaces of the blade 11. For limiting the movement of eccentric shaft 56 with bearings 54, into its two extreme positions, the finger piece 55 has an extension 61 coacting with stop surfaces 62 of the frame 50.

I believe that the nature of my invention and its operation and function will now be clearly understood by those skilled in the art.

I now claim:

1. In a device of the class described, a frame adapted for attachment to a razor containing a blade to be sharpened, a sharpener, mounting means on which said sharpener is movable relatively to said frame, means mounting said mounting means for adjustment movement in a fixed path relatively to said frame whereby said mounting means are maintained first in one position on said frame and at one point in the said fixed path and then in a second position on said frame displaced from said first position and at another point in the said fixed path, and a portion of said sharpener adapted to sharpen one side of the edge of the blade when the mounting means are in said one position and to sharpen the other side of the edge of said blade when the mounting means are in the second position.

2. In a device of the class described, a frame adapted for attachment to a razor containing a blade to be sharpened, a sharpener, mounting means on which said sharpener is movable relatively to said frame, means mounting said mounting means for adjustment movement in a fixed curved path relatively to said frame whereby to adjust the position in which said sharpener moves on said mounting means relatively to said frame, and a portion of said sharpener adapted to sharpen one side of the edge of said blade in each position of said mounting means.

3. In a device of the class described, a frame adapted for attachment to a razor containing a blade to be sharpened, a sharpener, mounting means on which said sharpener is movable relatively to said frame, eccentric means mounting said mounting means for adjustment movement in a fixed path relatively to said frame whereby to move said sharpener from a first position to a second position relatively to said frame, and said sharpener moving relatively to said mounting means in each position.

4. In a device of the class described, a frame, a sharpener, a shaft on which said sharpener is movable relatively to said frame, means mounting said shaft for eccentric adjustment movement on said frame whereby to move the axis of movement of said sharpener between two extreme positions for the cooperation of said sharpener with the upper and lower surfaces of a razor blade relatively to which said frame is secured, said shaft when in an intermediate position between said extreme positions holding said sharpener away from said razor blade.

5. In a device of the class described, a frame, a sharpener, mounting means on which said sharpener is movable relatively to said frame, eccentric means mounting said mounting means for movement on said frame whereby to move the axis of movement of said sharpener between two extreme positions on said frame for the co-

operation of said sharpener with the upper and lower surfaces of a razor blade relatively to which said frame is secured, said mounting means when in an intermediate position between said two extreme positions holding said sharpener away from said razor blade.

6. In a device of the class described, a frame adapted for attachment to a razor containing a blade to be sharpened, a sharpener, mounting means on which said sharpener is movable relatively to said frame, means mounting said mounting means for adjustment movement bodily relatively to said frame from one position to another whereby to change the position in which said sharpener moves on said mounting means and relatively to said frame, and detent means holding said mounting means against movement in at least two positions relatively to said frame.

7. In a device of the class described, a frame adapted for attachment to a razor containing a blade to be sharpened, a sharpener, mounting means on which said sharpener is movable relatively to said frame, eccentric means mounting said mounting means for adjustment movement with said sharpener from a first position to a second position relatively to said frame, said sharpener moving on said mounting means in each of said positions for sharpening the blade, and detent means holding said eccentric means against movement relatively to said frame in each of said positions.

8. In a device of the class described, a frame, a sharpener, mounting means on which said sharpener is movable relatively to said frame, eccentric means mounting said mounting means for movement with said sharpener from a first position where the sharpener is in contact with one side of a blade edge to be sharpened to a second position in which the sharpener is in contact with the other side of the blade edge to be sharpened, pinion and sector elements for rotating said eccentric means, and detent means on one of said elements for holding said eccentric means in each of said positions.

9. In a device of the class described, a frame, a sharpener, mounting means on which said sharpener is movable transversely of said frame, bearing means mounting said mounting means for movement in a fixed curved path relatively to said frame whereby to change the position in which said sharpener moves transversely of said frame, and weighted means on said sharpener for inducing reciprocation thereof on said mounting means through the transverse shaking of said frame.

10. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, and a sharpener mounted for movement on said shaft and for eccentric movement therewith whereby to bring its sharpener portion alternately into contact with the lower and upper faces of a blade carried by the razor to which said frame is applied.

11. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for movement on said shaft and for eccentric movement

therewith whereby to bring its sharpener portion alternately into contact with the lower and upper faces of a blade carried by the razor to which said frame is applied, a finger piece, means mounting said finger piece for pivotal movement on said frame, and means whereby said finger piece rotates said bearing members into two extreme positions to bring said sharpener portion against said upper and lower faces.

12. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for movement on said shaft and for eccentric movement therewith whereby to bring its sharpener portion alternately into contact with the lower and upper faces of a blade carried by the razor to which said frame is applied, a finger piece, means mounting said finger piece for pivotal movement on said frame, means whereby said finger piece rotates said bearing members into two extreme positions to bring said sharpener portion against said upper and lower faces, and detent means for yieldingly holding said finger piece in each of said positions to maintain said sharpener element in each of its two face contacting positions.

13. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for sliding movement on said shaft and for eccentric movement therewith whereby to bring its sharpener portion alternately into contact with the lower and upper faces of a blade carried by the razor to which said frame is applied, and weighted means on said sharpener for inducing reciprocation thereof through the transverse shaking of said frame.

14. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for sliding movement on said shaft and for eccentric movement therewith whereby to bring its sharpener portion alternately into contact with the lower and upper faces of a blade carried by the razor to which said frame is applied, a finger piece, means mounting said finger piece for pivotal movement on said frame, means whereby said finger piece rotates said bearing members into two extreme positions to bring said sharpener

60

portion against said upper and lower faces, and weighted means on said sharpener for inducing reciprocation thereof through the transverse shaking of said frame.

15. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for rotary and sliding movement on said shaft and for eccentric movement therewith whereby to bring its sharpener portion alternately into contact with the lower and upper faces of a blade carried by the razor to which said frame is applied, a finger piece, means mounting said finger piece for pivotal movement on said frame, means whereby said finger piece rotates said bearing members into two extreme positions to bring said sharpener portion against said upper and lower faces, and also into an intermediate position in which said sharpener portion is away from the blade, and guide means for said sharpener on said finger piece and sharpener for guiding the sharpener in its movement relatively to said eccentric shaft.

16. In a device of the class described, a frame having a pair of side plates, means securing said frame to a razor, a bearing member rotatably mounted in each of said plates for rotation in a single axis, a shaft supported at its opposed ends in said bearing members and in eccentric relation to said axis, a sharpener mounted for rotary and sliding movement on said shaft and for eccentric movement therewith whereby to bring its sharpener portion alternately into contact with the lower and upper faces of a blade carried by the razor to which said frame is applied, a finger piece, means mounting said finger piece for pivotal movement on said frame, means whereby said finger piece rotates said bearing members into two extreme positions to bring said sharpener portion against said upper and lower faces, and guide means for said sharpener on said finger piece and sharpener for guiding the sharpener in its movement relatively to said eccentric shaft.
